UNITED STATES PATENT OFFICE.

EVELINE FLORENCE JOHNSON, OF FOREST HILL GARDENS, LONG ISLAND, NEW YORK.

METHOD OF ATTACHING SEPARATE BORDERS TO HOUSEHOLD LINENS.

Application filed March 14, 1923. Serial No. 625,169.

To all whom it may concern:

Be it known that I, EVELINE FLORENCE JOHNSON, subject of the King of Great Britain and Ireland, residing at Forest Hills 5 Gardens, Long Island, New York, have invented new and useful Improvements in Methods of Attaching Separate Borders to Household Linens, of which the following is a specification.

10 My invention relates generally to household linens, such as table and bed coverings, napkins or the like, and has specific reference to an article of manufacture and a method of producing the same by attaching 15 separate borders thereto and by forming at the corners thereof what are generally known as "miter-corners."

In the needlework art it has long been the practice to form a border by folding a marginal strip of the material back upon itself to the desired depth, thereafter turning under a small edge and stitching it longitudinally thereof to the underlying body portion. Hem-stitching or other similar embroidery is generally included along the stitched edge of the border. To change the direction of the straight band or border to form a miter-corner, the band is cut at an abrupt angle, sacrificing a triangular piece, and thereby bringing the cut edges together and a line of stitching is run along the diagonal joint. This method of making borders is very satisfactory under general conditions, i. e. where the body and border are made of an integral piece of material, but when the condition arises where the border is to be of a color different from that of the body portion, the marginal strips must necessarily be stamped or dyed before the border is folded. The process of applying color to this marginal strip is more or less complicated and may only be performed under certain conditions, and as there are but few operators skilled in the art, production is curtailed and the cost of the finished article necessarily increased.

With the foregoing in mind it is the principal object of my invention to employ a method of attaching a separate border to a center body portion of the material and to join and fold the abutting ends of the border at the corners to give the general appearance of a "miter-corner." I accomplish this result by a method hereinafter described 55 which gives to the border all of the characteristics of the regularly made folded border

without sacrificing durability of construction or neatness in appearance.

The present invention is illustratively exemplified in the accompanying drawings, in 60 which, Figure 1 is a fragmentary view of one corner of a cloth showing a finished border as it appears according to my invention; Figure 2, is a view similar to Figure 1 with parts shown broken away to disclose the 65 fold of the border at the corner to form the miter; Figure 3, is a sectional view taken on the line 3—3 of Figure 1; and Figures 4 and 5 are perspective views of the corners of the article showing the ends of the borders attached together and the method of folding 70 the same to produce the miter-joint; Figure 6 is a substantially sectional view on the lines 6—6 of Figure 1.

Referring to the drawing, 10 denotes the 75 body or center portion of material having a hem-stitched marginal line 11 disposed between the body portion 10 and a narrow border 12.

The border proper, designated 13, is attached to the narrow border 12 and comprises a separate strip of material 13, 13' etc., for each edge of the body portion 10, each strip being formed by folding a single straight piece back upon itself along a longitudinal center line 14 and thereafter turning in the free edges, as shown in Figure 3. The folded pieces are attached to the narrow border 12 by placing the folded free edges of the border on opposite sides of the narrow 90 border 12 and along a line coincident with the outer edge of the hem-stitching 11. A line of stitching 15 is then run along the inside edge of the border 10, an operation which attaches both free edges of the border together and to the narrow border 12. At the corners the border strips 13, 13' etc., are cut off perpendicularly and project beyond the intersecting points of the lines of hem-stitching 11 a distance equal to their width. 100 The opposite ends of each border strip are designated *a* and *b*, respectively. The two perpendicularly cut ends *a* and *b* of adjacent borders 13 and 13' are then brought together so as to lie parallel to one another and to 105 slightly overlap, whereupon a line of stitching 16 is run through the two pieces, as clearly illustrated in Figure 4. The next step consists in causing one of the ends, designated *a*, of a border strip 13, i. e. at the line of stitching 16, to be disposed between the layers of material of the other folded 110

border piece 13', so as to bring the said end *a* against the folded longitudinal edge 14 of the said other strip 13', which projects at right angles thereto. As the end is being placed in position the attached ends, designated *b*, of the other border piece 13' will follow the end *a* and in doing so the layers of material will fold back upon themselves along a diagonal line extending from the 10 intersecting point of the hem-stitching 11 to the vertices of the right angle corner. The operation is completed by running a line of stitching 17 along this diagonal line of the fold, thereby firmly attaching the sections of 15 the miter-joint together and giving the finished appearance of the regularly made miter-corner.

It will be apparent in view of the method of attaching and mitering borders described 20 above, that such borders may not only be made up of separated strips of colored material, but may be further brought into contrast with the center or body portion 10 by employing materials of different texture and 25 design, the latter feature is particularly adapted for apron borders or other garments where two or more varieties of material are used in their construction.

What I claim is:—

30 1. A method of attaching borders and mitering the corners of the same in the manufacture of napkins or analogous articles,

which consists in attaching separate strips of longitudinally folded material to the edges of a center piece of material, thereafter attaching the adjacent ends of the strips together, and then folding the layers of one strip back upon themselves and along a diagonal line to cause the end of the other strip to be disposed between the folded ends 40 and against the line of the longitudinal fold of the first strip.

2. A method of attaching borders and mitering the corners of the same in the manufacture of napkins or analogous articles, 45 as claimed in claim 1, which further consists in stitching diagonal folds of one strip at the corner to each other and to the interposed portion of the other strip, substantially as described.

3. As a new and improved article of manufacture, a bordered article having the border thereof made of separate strips of material each of which is folded longitudinally thereof and the inner edges attached to the body on opposite sides thereof, the said strips projecting beyond the corners of the body and being attached together at their ends at each corner, one strip being folded 55 inwardly along a diagonal line and the end 60 of the other strip projecting to the longitudinal fold of the first strip.

In testimony whereof I affix my signature.
EVELINE FLORENCE JOHNSON.
